UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BINDER.

1,238,846.

Specification of Letters Patent.

Patented Sept. 4, 1917.

Application filed November 17, 1916. Serial No. 131,814.

To all whom it may concern:

Be it known that I, CLARENCE D. TRUSSELL, a citizen of the United States, residing in Poughkeepsie, in the county of Dutchess 5 and State of New York, have invented certain new and useful Improvements in Loose-Leaf Binders, of which the following is a specification.

My invention relates to a loose leaf binding mechanism and particularly to that type of device wherein a plurality of prongs or hooks or half rings are mounted on hook plates which are pivotally supported and are spring held in either open or closed position. 10 15 My invention has for its object to provide an improved and simple construction of such loose leaf binder. A further object of my invention is to improve the means of attaching the binder to the cover, and likewise to 20 improve the construction of hook.

Desirable forms in which my invention may be embodied are illustrated in the accompanying drawings, wherein,—

Figure 1 is a perspective view of a binder 25 embodying my invention;

Fig. 2 is a sectional detailed view thereof taken on the line 2—2 of Fig. 1;

Fig. 3 is a face view of the device showing the hooks open partly broken;

Fig. 4 is a section on the line 4—4 of Fig. 3 showing the hooks open;

Fig. 5 is a similar section of the same parts in closed position;

Fig. 6 is a sectional view similar to Fig. 4 of a modified form of device;

Fig. 7 is a sectional view of a further modification;

Fig. 8 is a back view of my device;

Fig. 9 and Fig. 10 are perspective views 40 of hubs employed to attach the binding mechanism to the cover; and

Fig. 11 is a face view of the hook plates detached in the modification illustrated in Fig. 7.

According to my invention means are provided for supporting the hook plates and holding them by spring means in open or closed position, which are greatly simplified. 45 For this purpose but two elements are necessary, (1) the hook plates and (2) a supporting plate in which the hook plates are pivotally mounted. These with the spring are all the elements that are essential for the mechanical operation of the device, although

I also prefer to employ a back plate which 55 is suitably secured to the supporting plate in order to provide means for conveniently attaching the device to the cover.

In the embodiment of my invention shown in the accompanying drawings the hook 60 plates A A¹ are pivotally supported at or near their outer ends in a flat supporting plate B. Such pivotal support of the hooks in the said plate may be provided by means of lugs C, with which each hook plate is 65 furnished adjacent its outer edge, and each hook plate preferably has a plurality of the said lugs, and these lugs may pass through perforations C¹ in the supporting plate. If desired such pivotal supporting means may 70 otherwise be furnished as by means of flanges D with which each edge of the supporting plate may be provided as illustrated in Fig. 6, and these flanges, as they are shown, extend downwardly and serve to embrace the outer edges of the hook plates. 75

The spring means for causing the hook plates to pass to either open or closed position and to be held in such position, comprise projections E with which each hook 80 plate is provided adjacent its inner edge. As illustrated, such projections are in the form of lugs bent up from the material of which the hook plates are formed. These projections are adapted to extend through 85 or into openings in the hook plates and for this purpose, as illustrated, the hook plates are provided with an opening or channel F through which the projections pass, as illustrated in Fig. 4. For the purpose of conveniently inclosing the parts, a housing F¹ 90 may be employed for the said opening and projections, as illustrated in said figure. The opening in the supporting plate and the housing are shown as formed by striking 95 up or embossing a portion of the supporting plate. The projections E on the respective plates are preferably arranged in groups, and each group should have at least three projections so arranged that a projection on 100 one plate is located between two projections on the opposite plate, as is clearly shown in Fig. 3. Any desired number of groups may be employed and any desired number of projections greater than three in each group. 105 The spring means employed by me may be of various forms. As illustrated, such spring means take the form of a spring rod

G which is longitudinally disposed between the respective projections at or near the ends thereof, and for this purpose one or more of said projections may be provided with 5 notches or anchorages G¹ to hold the said rod in place.

In the forms of my invention illustrated in Figs. 4, 5 and 6 the supporting plate is on top and the hook plates are located beneath 10 the supporting plate, and this furnishes a very desirable and convenient arrangement of parts. It is not, however, indispensable to the employment of my invention, as I have shown in Fig. 7 a construction wherein the 15 hook plates are located above the supporting plate, the parts being otherwise similarly constructed. In the form of my invention illustrated in Figs. 4, 5 and 6 the respective movements of the hook plates are limited as 20 follows: The opening movement is limited by the contact of the hook plates with the under side of the supporting plate; the closing movement is limited by contact of a pair of the hooks H which each of the hook plates 25 carries. In the form of my invention illustrated in Fig. 7 wherein the hook plates are disposed above the supporting plate means must be provided to limit the opening movement of the hook plates, and for such purpose 30 the lugs I are well adapted and have heretofore been employed for a similar purpose. See for instance my Patent No. 1,141,157. Each hook plate is provided with one or 35 more of the lugs I, and these lugs extend down through the opening E in the hook plate and each has its free end located beneath the opposite hook plate so that upon the opening movement such lugs will by contact with the underside of the supporting 40 plate B limit the opening movement of the hook plates.

My invention contemplates improved means for attaching the loose leaf binding device invented by me to the cover. I have 45 illustrated the device as being provided with a cover J which may be any one of the designs of covers usually employed. For the purpose of enabling the attachment of the parts to be easily made, I have illustrated the 50 employment of a back plate K which is provided with longitudinal edge flanges k that are adapted to hold the back plate in position upon the supporting plate B. The said attaching means comprise metallic hubs L of 55 which any suitable number may be employed. In Fig. 8 I have illustrated the employment of five such hubs. These hubs may well be used in connection with a binding plate X and by means of which the hubs M are firmly 60 clamped to the back of the cover J. Other means might be employed for this purpose, or if desired the hubs M might be directly clamped to the binding mechanism, but the arrangement which I have illustrated is a 65 desirable one and convenient and economical

for purposes of manufacture. Each hub L is preferably curved longitudinally for the purpose of conforming to the shape of the binding plate X, the back plate K and the back of the book. Each of the said hubs has a 70 portion M which is located outside of the back of the cover J. The hubs have side flanges N which pass through cuts in the cover J, leather being frequently employed for such cover. Upon the said side flanges 75 are lugs O which are bent down on the binding plate X as illustrated in Fig. 2 and securely hold the parts together. Any desired number of said lugs on the hubs may be employed. I prefer to employ a plurality of 80 lugs on each side, as illustrated in Fig. 10 wherein two such lugs on each side are shown. The binding plate X is provided with lugs Y which pass through slots in the back plate and are bent down to secure the 85 binding mechanism to the cover.

I have illustrated in the accompanying drawings the most desirable form of my invention now known to me, but the same may be modified and changes made therein, and 90 equivalent devices substituted for those illustrated, within the limits of the appended claims.

What I claim is:—

1. A loose leaf binder comprising a flat 95 supporting plate, and hook plates pivotally connected thereto adjacent their outer edges and having near their meeting edges projections adapted to extend through the plane of said supporting plate and movable to 100 either side of the plane of said pivots, the projections on said respective hook plates being resiliently connected to hold the hook plates in open or closed positions.

2. A loose leaf binder comprising a flat 105 supporting plate, hook plates pivotally mounted adjacent their outer edges in said supporting plate, and having projections adapted to extend through the plane of said supporting plate and movable to either side 110 of the plane of said pivots, and springs between the projections on said respective hook plates.

3. A loose leaf binder comprising a flat 115 supporting plate, hook plates having lugs adjacent their outer edges entering perforations adjacent the outer edges of said supporting plate and providing pivotal supports for said hook plates in said supporting plate, said respective hook plates, having 120 projections adapted to extend through said supporting plate past the plane of said pivots, and springs between the projections on said respective hook plates.

4. A loose leaf binder comprising a flat 125 supporting plate, having bearings adjacent its outer edges, hook plates pivotally mounted in said bearings, said respective hook plates having projections adapted to extend through said supporting plate past the 130

plane of said pivots, and springs between the projections on said respective hook plates.

5. A loose leaf binder comprising a flat supporting plate, hook plates located below said supporting plate and pivotally mounted at their outer edges in said supporting plate, said respective hook plates having projections adapted to extend through the body of said supporting plate past the plane of said pivots, and springs between the respective projections.

6. A loose leaf binder comprising a flat supporting plate, hook plates movable to a plane parallel with and adjacent said supporting plate and pivotally mounted at their outer edges in said supporting plate, said respective hook plates having projections adapted to extend through the body of said supporting plate past the plane of said pivots, springs between the respective projections, and means for limiting the movement of said hook plates away from said parallel plane.

25 7. A loose leaf binder comprising a flat supporting plate, hook plates pivotally mounted at their outer edges in said supporting plate, said respective hook plates having projections adapted to extend through the body of said supporting plate, and a spring rod between the ends of said respective projections adapted to pass to one side or the other of a line between said pivots as the hooks are open or closed.

35 8. A loose leaf binder comprising a flat supporting plate, hook plates located below said supporting plate and pivotally mounted at their outer edges in said supporting plate, projections on said respective hook plates having their ends adapted to extend through the body of said supporting plate past the plane of said pivots, and springs between the respective projections, said hook plates adapted to be substantially parallel with said supporting plate when the hooks are open, and oppositely disposed hooks or half rings on said respective hook plates.

9. A loose leaf binder comprising a flat supporting plate, hook plates located below said supporting plate and pivotally mounted at their outer edges in said supporting plate, projections on said respective hook plates having their ends adapted to extend through the body of said supporting plate past the plane of said pivots, and springs between the respective projections, the movement of said hook plates being limited by said supporting plate in one direction and by the contact of the ends of the hooks in the other direction.

10. A loose leaf binder comprising a flat supporting plate, and hook plates pivotally connected thereto adjacent their outer edges and having near their meeting edges projections adapted to extend up through the

plane of the supporting plate, and the supporting plate formed with integral housings to receive said projections.

11. A loose leaf binder comprising a flat supporting plate having slots in its outer edges and openings near its middle, and hook plates having projections near their outer edges entering said outer slots to form pivotal connections, and having near their meeting edges projections adapted to enter said openings, the projections on the respective hook plates being resiliently connected.

12. A loose leaf binder comprising a flat supporting plate, hook plates pivotally mounted adjacent their outer edges in said supporting plate, projections on the respective hook plates adjacent their inner edges arranged in a group or groups of three and adapted to extend through said plate, and a spring or springs between said respective projections, said springs adapted to pass to opposite sides of a line between said pivots as the hooks are opened and closed.

13. A loose leaf binder comprising a flat supporting plate, hook plates pivotally mounted adjacent their outer edges in said supporting plate, projections on the respective hook plates adjacent their inner edges adapted to extend through said plate, and a spring between said respective projections, said spring adapted to pass to opposite sides of a line between said pivots as the hooks are opened and closed, said hook plates adapted to lie close against and substantially parallel with said supporting plate in one of their extreme positions.

14. A loose leaf binder comprising a supporting plate, hook plates having pivotal supports in said supporting plate, projections from said hook plates adjacent their inner edges extending through said supporting plate so disposed that a projection on one hook plate is located between a pair of projections on the mating hook plate, and a spring between said projections.

15. A loose leaf binder comprising a supporting plate, hook plates having pivotal supports in said supporting plate, said hook plates having projections adjacent their inner edges extending through said supporting plate so disposed that a projection on one hook plate is located between a pair of projections on the mating hook plate, and a spring rod longitudinally disposed between the said projections.

16. A loose leaf binder comprising a supporting plate, hook plates having pivotal supports in said supporting plate, said hook plates having projections adjacent their inner edges extending through said supporting plate so disposed that a projection on one hook plate is located between a pair of projections on the mating hook plate, and a spring rod longitudinally disposed between the said projections.

the said projections, said projections having notches receiving said rod.

17. A loose leaf binder comprising a supporting plate, hook plates having pivotal supports in said supporting plate, said hook plates having projections adjacent their inner edges extending through said supporting plate so disposed that a projection on one hook plate is located between a pair of 10 projections on the mating hook plate, and a spring rod longitudinally disposed between the said projections and adapted to pass to opposite sides of a line between said pivots as said hooks are opened and closed.

18. A loose leaf binder comprising a supporting plate, hook plates having pivotal supports in said supporting plate, said hook plates having projections adjacent their inner edges adapted to extend through said 20 supporting plate, a spring between said projections, a back plate, a cover and means for securing said back plate to said cover comprising hubs adapted to be located on the outside of said cover, having flanges adapted 25 to pass through said cover, and lugs on said flanges adapted to retain said back plate in place.

19. A loose leaf binder comprising a supporting plate, hook plates having pivotal supports in said supporting plate, said hook plates having projections adjacent their inner edges adapted to extend through said supporting plate, springs between said projections, a back plate, a cover and means for 30 securing said back plate to said cover comprising hubs adapted to be located on the outside of said cover, having flanges adapted to pass through said cover, and a plurality of lugs on each flange, adapted to retain said 35 back plate in place.

20. A loose leaf binding mechanism, comprising a binding plate, a cover and means for attaching them together comprising a hub adapted to be located on the outside of 40 said cover, and having flanges adapted to

pass through said cover, and lugs on said flanges adapted to be bent over against said binding plate.

21. A loose leaf binding mechanism, a cover and means for attaching them together 50 comprising a hub adapted to be located on the outside of the said cover, having its outer face curved longitudinally, and having flanges adapted to pass through said cover, and lugs on said flanges adapted to be bent 55 over against said binding mechanism.

22. A loose leaf binding mechanism, a cover and means for attaching them together comprising a hub adapted to be located on the outside of the cover, and having flanges 60 adapted to pass through said cover, and a plurality of lugs on each flange adapted to pass through and be bent over against said binding mechanism.

23. A loose leaf binder comprising a supporting plate, hook plates pivotally mounted adjacent their outer edges in said supporting plate, and having projecting inner portions adapted to extend through said supporting plate, a spring between the said respective 70 projections and adapted to pass to one side or the other of a line between the said pivots as the hooks are opened and closed, and hooks mounted on the said hook plates, each of substantially half round form, and having a portion at or near the attachment of the hook plates bent outwardly from the arc of the circle in which the body of the hook is formed. 75

24. In a loose leaf binder, a supporting plate, oppositely disposed hook plates having bearings in said supporting plate, said supporting plate being straight between said bearings and said hook plates having portions adapted to pass to opposite sides of a line between said bearings as the hook plates are moved. 80

In witness whereof, I have hereunto signed my name. CLARENCE D. TRUSSELL.
